UNITED STATES PATENT OFFICE.

FLOYD N. PERKINS, OF CLEVELAND, ASSIGNOR TO THE KENTON LOCK MANUFACTURING COMPANY, OF KENTON, OHIO.

LATCH.

SPECIFICATION forming part of Letters Patent No. 433,146, dated July 29, 1890.

Application filed May 21, 1889. Serial No. 311,601. (Model.)

To all whom it may concern:

Be it known that I, FLOYD N. PERKINS, a citizen of the United States, residing at Cleveland, in the county of Cuyahoga and State of Ohio, have invented certain new and useful Improvements in Door-Latches; and I do hereby declare that the following is a full, clear, and exact description of the invention, which will enable others skilled in the art to which it appertains to make and use the same.

My invention relates to improvements in door-latches; and the invention consists in the construction shown and described, and particularly pointed out in the claims.

In the accompanying drawings, Figure 1 is a plan view of a latch and lock-ease, with enough of the casing broken away to disclose the latch and its associated mechanism. Fig. 2 is a view of the rear upper corner of Fig. 1, with the latch removed and showing the lock in position to engage the lever and prevent the latch from opening. Fig. 3 is a detail of the lever and the hub as they stand in relation to one another in their normal position. Fig. 4 is a section of the casing in the corner which supports the hub and lever. (Shown also in Figs. 1 and 2, but with the face of the case partly covered.) Fig. 5 is a side elevation of the hub, showing the recess in its side, in which a projection on the lever works. Fig. 6 is a detail in perspective of the lever, and Fig. 7 a view of a section of the rear edge of the casing, disclosing the projections on the case and on the lock, respectively, whereby the lock is held in either adjusted position, as hereinafter described.

I am aware that a latch or bolt, lever, and hub have been used before in the general relation here shown, and I do not claim them as new, broadly; but I am not aware that the special construction herein shown and described has ever before been known or used.

Among the advantages of the device as made by me are compactness and ease of operation, and these advantages result from the novel construction of the parts, as I shall now proceed to describe.

10 represents the hub, in which the spindle of the handle, by which the latch is operated, is supported in the usual angular axial opening a' . This hub is provided with a recess a' in its side, made deep enough to expose the

opening a , as seen in Fig. 5, but leaving the hub intact above and below the opening. The lever B is set to closely encircle the hub. A about half-way round, and has a projection b , which enters the recess a' , and is so arranged as to work in said recess. The fulcrum-point of the lever is close to the hub, as shown, at the angular shoulder b' on the lever, which bears against a rib d on the casing. The base b^2 of the lever normally lies flat against the upturned flange or edge of the casing, between ribs d and d' , and the arm b^3 of the lever extends past the hub and has a flat bearing-surface b^4 , engaged by the short arm a^2 of the hub. The stem of the latch C is perforated to connect with the post b^5 on the lever. A suitable spring D bears against the outer extremity of the base b^2 of the lever, and serves to carry all the parts back to the position of rest after the latch has been opened, as seen in Fig. 1. On the under side of the arm of the lever is a slight lug b^6 , which works in a segmental groove a^4 in the case. The curvature of the groove a^4 corresponds to the fulcrum-point b' as the center of the curve, and the projection b , working in recess a' of the hub, serves to keep the lug b^6 in the groove while the hub turns in opening the latch.

In operation when the hub is turned by the handle the arm a^2 , bearing against the surface b^4 of the lever, presses that end of the lever back, thus retracting the latch and drawing it wholly within the case. When this is done, the lever turns on its fulcrum, to which it is held by the joint action of the hub, the segmental groove a^4 in the case, and the spring. The several parts are so bestowed about the hub that the operation of the latch is performed with the greatest possible ease, considering the distance it is to be moved, as it is placed directly by the side of the hub near its axial center instead of being carried to the lower part of the case and operated through a long arm, as in other latches in common use. By my construction I am enabled to get the works nearer to the edge of the case than was possible with the old form, and this makes room for latch and locking bolt in a correspondingly-smaller case than formerly was necessary. The latch comes above and the locking-bolt below in their natural order,

whereas with the old construction these parts were necessarily reversed.

E represents a lock pivoted on a post e on the case, and adapted to engage a shoulder b⁸ on the back of the lever B to prevent the latch from being opened. In Fig. 1 the lock is shown as swung out of locking position and in Fig. 2 as in locking position. A slight rib or projection e' on the case, Fig. 7, and a corresponding rib or projection e² on the bottom of the lock, with a spring e³ to hold the lock down operates to hold the lock down in either position.

It will be observed that the arm b⁸ of the lever extends at right angles to the base b² and has a semicircular curve or depression b', which surrounds the hub. This curvature about the hub enables me to bring the arm to one side of the hub, where it makes free connection with the latch-stem for the longitudinal movement thereof, and at the same time comes near to the hub in such relation that a very short arm thereon will move the latch the requisite distance.

Having thus described my invention, what I claim as new, and desire to secure by Letters Patent, is—

1. In door-latches, the casing provided with a groove a⁴ on its inner side, extending in a curved line from the opening for the spindle, a hub provided with an axial opening for the spindle, a recess a' in its side, and an arm a², in combination with a spindle a and a lever B, having a projection b entering the recess in the hub, an arm b⁸, which is engaged by the arm a², and a projection b⁴ on its under side working in the groove a⁴ in the casing, substantially as set forth.

2. In a door-latch, the lever provided with a base resting against the edge of the case, a post for the latch, and a shoulder for the lock near the post, in combination with a lock to engage said shoulder, and a hub with an arm to operate the lever, substantially as set forth.

FLOYD N. PERKINS.
